United States Patent Office

Des. 216,250
Patented Dec. 9, 1969

216,250

BOTTLE

Stephen J. Kneapler, Miami, Fla., assignor to Richford Corporation, Farmingdale, N.Y., a corporation of New York

Filed Nov. 21, 1968, Ser. No. 14,581

Term of patent 14 years

Int. Cl. D9—01

U.S. Cl. D9—147

FIG. 1

FIG. 2

FIG. 3

FIG. 1 is a front elevational view of a bottle embodying my new design;

FIG. 2 is a top plan view thereof;

FIG. 3 is a bottom plan view thereof.

The dominant features of my design reside in the portions shown in full lines.

I claim:

The ornamental design for a bottle, substantially as shown and described.
